UNITED STATES PATENT OFFICE.

THOMAS FRANCIS BALLISTER AND HENRY GOEDINGHAUS, OF SANTA MARIA,
CALIFORNIA.

DRIER.

Application filed March 9, 1922. Serial No. 542,448.

To all whom it may concern:

Be it known that we, THOMAS F. BALLISTER and HENRY GOEDINGHAUS, citizens of the United States, and residents of Santa Maria, 5 in the county of Santa Barbara and State of California, have invented certain new and useful Improvements in Driers, of which the following is a specification.

This invention relates to driers and deodorizers especially adapted for use in the dry cleaning industry, laundry and home laundry and other industries requiring rapid drying or deodorizing processes.

An important object of this invention is to 15 provide a drier and deodorizer which is strictly portable so that the same may be conveniently set up in any desired place and also so that the same may be transported to the point of use in an expeditious and economical manner.

Further the invention forming the subject matter of this application aims to provide a drier and deodorizer which overcomes the necessity of employing a boiler and the machine fittings usually employed in connection with driers for clothing, laundries, and other establishments needing a rapid drying and deodorizing process.

Further the invention aims to provide a 30 drier and deodorizer which is of highly simplified construction, economical to construct and operate and durable in use.

Other objects and advantages of the invention will be apparent during the course of 35 the following description.

In the accompanying drawings forming a part of this application, and in which like numerals are employed to designate like parts throughout the same,

40 Figure 1 is a side elevation of the improved drier and deodorizer, parts being shown in section,

Figure 2 is an end elevation of the improved drier and deodorizer,

45 Figure 3 is a vertical transverse sectional view taken on line 3—3 of Figure 1.

In the drawing wherein for the purpose of illustration is shown a preferred embodiment of the invention the cabinet is generally 50 designated by the numeral 5 and consists of spaced parallel sides 6 preferably formed from tongue and groove material, whereby to strengthen the side walls and to provide a cabinet which is neat in appearance.

55 The spaced parallel side walls 6 are securely

and detachably connected to the end wall 8 by means of longitudinally extending connecting strips 10 and end strips 11 which are connected to the side strips by means of fastening bolts 12. As illustrated in Fig. 1 the 60 fastening bolts or straps 12 are secured to the longitudinally extending strips 10 and pass through the end portions of the cross strips 11 and are provided with nuts which may be tightened on the bolts for drawing 65 the end strips firmly into engagement with the end walls and into engagement with the ends of the side strips. It is thus seen that the side walls are detachably though securely connected to the end walls in such a 70 manner that the cabinet may be taken apart when desired for shipment or other purposes. The strips 10 and 11 are secured to the lower portion of the cabinet and to the intermediate portion of the same while additional strips 16 and 17 are carried by the top 18 and are engaged with the upper portions of the side and end walls. The strips 16 of which there are two and which extend longitudinally of the cabinet are provided 80 at their ends with connecting bolts 19 extended through the end strips 17 and secured thereto by means of nuts 20. The strips 16 and 17 extend down from the top 18 and engage the side and end walls of the drier so 85 that when the nuts 20 are tightened on the bolts the side and end walls will be securely engaged for securing the top in position. Therefore, the side and end strips 16 and 17 respectively not only serve as a means for 90 connecting the upper portions of the side and end walls but also serve as a means for detachably securing the top in position.

One of the side walls 6 is provided with a door 25 through which an attendant may 95 pass and the interior of the cabinet is as illustrated in Figure 3 provided with longitudinally extending poles 28 with which the coat hangers 30 may be engaged. As illustrated in Figure 3 the longitudinally extending poles or tubular members 28 are arranged in spaced relation within the cabinet so as to support the garments in proper position within the cabinet.

In carrying out the invention a burner 33 105 is arranged in the lower portion of the cabinet at one end of the same and may be supplied with gas by means of a pipe 34 extending from a suitable source of supply. A valve 35 is interposed in the pipe 34 and 110

forms a means whereby the burner may be regulated.

An air control member 37 of any desired type is arranged at the inlet end of the burner and may, of course, be adjusted to regulate the amount of air supplied to the burner. With reference to Figures 1 and 2 it may be seen that the burner casing 40 is extended beyond the cabinet and has one end formed with an opening 42 which forms a means through which a match or the like may be introduced into the casing for lighting the gas. A protecting plate 44 may be arranged beneath the burner while a similar protecting plate of any desired material may be secured to the end of the cabinet adjacent the burner. In carrying out the invention a pair of metal plates 46 may be secured to that end of the drier which supports the burner and the plates prevent the end wall of the drier from burning.

As illustrated in Figure 1 an exhaust pipe 48 is extended longitudinally through the lower portion of the cabinet and is then extended upwardly to a suitable point of discharge. It will be seen that the exhaust pipe 48 extends centrally through the major portion of the cabinet so as to give off a quantity of heat to cause garments within the drier to be quickly dried.

Air may enter the cabinet through a plurality of air inlet openings 50 in the lower portion of the side and end walls and air may be discharged by way of a vent pipe 52 connected to the top of the cabinet. A suitable damper 53 is arranged in the vent pipe 52 and forms a means whereby the passage of heated air from the cabinet may be controlled.

In operation, garments are arranged within the cabinet and the burner is lighted so that the heat radiating from the burner is caused to quickly dry the garments. Also the odor of the cleaning medium is removed from the garment by the passage of the heat through the garment.

The improved drier and deodorizer is strictly portable and may be quickly set up

or taken down and in carrying out the invention an oil, gasoline or wood burner may be employed in lieu of the gas burner. However, in any case the flame from the burner is prevented from coming in contact with the garment by reason of the casing 40 which surrounds the burner.

Having thus described the invention, what is claimed is:—

1. A portable drier and deodorizer comprising a cabinet inclusive of side and end walls, and strips extending about the side and end walls and having their end portions detachably connected whereby to detachably connect the side and end walls.

2. A portable drier and deodorizer comprising a cabinet inclusive of side and end walls, strips extending about the side and end walls and having their end portions detachably connected whereby to detachably connect the side and end walls, and a top applied to said side and end walls and having depending attaching strips engaging the side and end walls and having means whereby the same may be drawn together for securing the top in position.

3. A drier and deodorizer for use in dry cleaning comprising a cabinet inclusive of side and end walls, longitudinally extending strips arranged exteriorly of said side walls, end strips arranged exteriorly of said end walls, and bolts connected to said side strips and extending through said end strips and nuts threaded on said bolts for securely connecting the end strips to the side strips.

4. A drier and deodorizer for use in the dry cleaning industry comprising a cabinet inclusive of side and end walls, a top mounted on said side and end walls and having depending strips contacting with the side and end walls, and fastening devices associated with the ends of said strips and having means for securely engaging the side and end walls whereby to hold the top in position.

THOMAS FRANCIS BALLISTER.
HENRY GOEDINGHAUS.
